Patented Apr. 30, 1918.

Attorney

UNITED STATES PATENT OFFICE.

JOHN A. STRANSKY, OF PUKWANA, SOUTH DAKOTA.

AIR-MIXING DEVICE.

1,264,221.

Specification of Letters Patent. Patented Apr. 30, 1918.

Application filed March 13, 1917. Serial No. 154,492.

To all whom it may concern:

Be it known that I, JOHN A. STRANSKY, a citizen of the United States, and resident of Pukwana, in the county of Brule and 5 State of South Dakota, have invented certain new and useful Improvements in Air-Mixing Devices, of which the following is a specification.

This invention relates to charge forming 10 devices for explosive engines and has more especial reference to a novel air supply device therefor.

The dominant object of the invention is to provide a device adapted for arrangement 15 between the carbureter and intake manifold of an engine, whereby, a quantity of air will be automatically admitted to the explosive charge, thus, enriching the same and lending to the power thereof.

Another object of the invention is to provide means for automatically admitting air in varying quantities, at predetermined periods, depending upon the speed of the engine.

Other and further improvements and novel details in the construction and arrangement of the various parts of the device will be brought out more in detail in the description to follow, which, for a clear understanding of the invention should be considered in connection with the accompanying drawings forming a part hereof, and wherein is disclosed for the purpose of illustration, a convenient and satisfactory 35 embodiment of the invention.

In the drawings:

Figure 1 is a vertical section through the improved air mixing device as applied between the adjacent extremities of a carbureter and intake manifold; and

Fig. 2 is a front elevation thereof with parts broken away and shown in section.

Referring now more specifically to the drawings, and in connection with which like reference numerals will refer to corresponding parts throughout the several views, there is provided an apertured plate designated 1, the aperture in the said plate being of a size and shape complementary to the discharge 50 end of the carbureter and the intake manifold, while the plate is of a size and shape complementary to the flanged adjacent extremities of the discharge portion of the carbureter and the intake manifold, whereby, 55 the same may be securely fastened therebetween by passing bolts or other suitable fas-

tening devices through the aligned apertures in the flanged portions of the carbureter discharge and intake manifold and similar openings 2 formed in the said plate. Obviously, by so arranging the plate 1 between the carbureter and the intake manifold, the necessity of drilling or cutting the same is obviated. A screen of fine mesh 3 is arranged over the aperture in the plate 1 and serves as means for thoroughly vaporizing the explosive charge as delivered from the carbureter. A plurality of parallel ways 4 are formed in the intake 1 and communicate with the apertures therein, the lower 70 portions of the said ways extending through externally screw threaded nipples 5 formed upon the said plate 1, whereby cylindrical valves cages 6, varying in size may be turned into engagement therewith. Intake openings 7 are formed within the bottoms of the cages and are normally closed through the medium of spherical valve members 8, which members are of different size and weight, as shown in the Fig. 2. In this connection, it 80 is to be noted, that if desired, the ways 4 extending through the plate 1 may be varied in size to accord with their respective valve cages 6, such as conditions or preference may dictate.

In operation, the engine when running at low speed will create sufficient suction in the intake manifold thereof to unseat the smaller of the spherical valves, thus, admitting a charge of air to the intake manifold 90 and enriching the explosive charge being conveyed therethrough. However, should the speed of the engine be increased, the suction too would be increased, thus, unseating the larger of the spherical valves and 95 permitting a greater quantity of air to be admitted to the intake manifold. It is to be understood, that such suction as may be created during the initiative starting of the engine is not sufficient to unseat the spherical valves 8 and as a consequence, will not interfere with such operation.

Manifestly, the construction shown is capable of considerable modification and such modification as is within the scope of my 105 claims, I consider within the spirit of my invention.

I claim:

1. In a device of the character described, an apertured plate having a plurality of 110 parallel ways varying in size formed therein and communicating with the aperture, screw

threaded nipples formed upon the plate adjacent said ways, valve cages, varying in size connected with said nipples, and spherical valves varying in size arranged in the cages and adapted to be operated at predetermined periods.

2. In a device of the character described, an apertured plate having a plurality of parallel ways varying in size formed therein and communicating with the aperture, a

screen arranged over the aperture, a plurality of screw threaded nipples formed upon the bottom of the plate adjacent said ways, valve cages turned into engagement with said nipples, and spherical valves arranged in the cages varying in size and operable at predetermined intervals. ¹⁵

In testimony whereof, I affix my signature hereto.

JOHN A. STRANSKY.
